UNITED STATES PATENT OFFICE.

JAMES EDWARD BALDWIN, OF HEMPSTEAD, NEW YORK.

SUBMERSIBLE PUMP.

Application filed January 7, 1921, Serial No. 435,620. Renewed July 17, 1926.

This invention relates to power pumps of the submersible type.

In devices of this character the power is usually furnished by an electric motor directly connected with the pump, which ordinarily is of the centrifugal type, the impeller of the pump in such cases being mounted on an extension of the motor shaft. A considerable difficulty heretofore experienced with pumps of this character arises from water working along the pump shaft into the motor compartment, this despite the fact that a gland or stuffing box is usually provided at the motor side of the pump. Attempts have been made to overcome this difficulty by lengthening the motor shaft, by mounting the motor in a "diving bell" chamber and the like, but all these expedients have resulted in bulky and cumbersome constructions which are effective only when the pump structure is supported in an upright position.

My invention aims to overcome the above objections and to provide a relatively simple and compact structure in which leakage into the motor compartment will be effectually prevented.

In the accompanying drawings I have illustrated a practical and for the present a preferred embodiment of the invention, but wish it understood that changes and modifications may be resorted to without departure from the true spirit of the invention, as will be apparent from the scope of the appended claims.

Figure 1 in the drawings referred to is a longitudinal section and part side elevation view of the complete pump unit.

Figure 2 is an enlarged cross sectional view of the same as taken on substantially the plane of line 2—2 of Figure 1.

The pump section of the apparatus comprises a pump casing 5 having an axial inlet 6 and an outlet (the latter not shown) and an impeller 7 rotating within the casing.

The motor section of the apparatus comprises an electric motor indicated generally at 8 and enclosed within a water-tight casing 9.

In my invention there is interposed between the motor casing and the pump casing, a compartment or chamber 10 and the motor shaft 11 extends from the motor compartment through this intermediate chamber to the pump casing, where it serves as the support for the impeller.

Within the intermediate chamber 10 and surrounding the combination motor and pump shaft there is a pump packing or gland 12 connected with the journal extension 13 of the pump casing and a second packing or gland 14 connected with an extension 15 of a part of the motor bearing.

The intermediate compartment 10 serves in effect as a collection chamber for any water or oil leaking past the pump packing and the additional packing at the motor side of the collection chamber prevents leakage along the shaft from the collection chamber into the motor chamber.

To give access to these packings for the purpose of adjustment, renewal or inspection, I have shown the collection chamber as having a door or hand hole cover 16 in one side thereof which is made water-tight as by means of a suitable gasket 17 and clamp screws 18. This cover is shown as hinged at its lower end at 19 and the bottom of the chamber is shown as substantially horizontal so as to drain itself when the door is swung open.

In practice, the collection chamber may be and preferably is formed as an extension of the shell or casing of the motor and the pump casing is bolted to the open end of such extension so as to form an end cover therefor.

The invention, it will be seen, is entirely practical and wholly overcomes the objections noted above. The packings between the collection chamber and pump unit and between the collection chamber and motor unit are, it will be observed, individually adjustable to take up for wear and to prevent leakage at either of these points and such adjustments are made easily possible by the ready accessibility afforded by the wide-opening cover at the side of the chamber. With the construction disclosed the pump can be operated as well horizontally or vertically or in any intermediate position.

What I claim is:

1. A submersible pump of the character described having a motor compartment and a pump casing in longitudinal alignment, a collection chamber located between the compartment and the casing, closed walls separating the chamber from the compartment and the casing, a packing mounted on each wall, a shaft extending through the packings, the collection chamber having a drain-

- age opening leading therefrom, and a manually-operated closure for closing said opening and rendering the chamber completely closed before the pump is submerged.
5. 2. A submersible pump of the character described having a motor compartment and a pump casing in longitudinal alignment, a collection chamber located between the compartment and the casing, closed walls 10 separating the chamber from the compartment and the casing, a packing mounted on each wall, a shaft extending through the packings, said chamber having an aperture leading from said chamber for draining liquids from the chamber and for access to 15 the packings, and a water-tight closure for closing said aperture, thereby rendering the chamber completely closed before the pump is submerged.
10. 3. In a pump of the character described having a motor compartment, a collection

chamber and a pump casing in longitudinal alignment, said collection chamber being formed by integral cup shaped extensions on the respective motor compartment and the pump casing, means for fixedly securing the terminal ends of said extensions in mating relation, a motor within the motor compartment and provided with a shaft extending from said compartment through the collection chamber and into the pump casing, a pump element on said shaft within the pump casing, adjustable packings on the motor shaft within the collection chamber between said chamber and the motor compartment and said chamber and the pump casing, one side of the collection chamber having an opening therein for the full height thereof and a water tight closure for said opening.

In testimony whereof I affix my signature.
JAMES EDWARD BALDWIN.
